UNITED STATES PATENT OFFICE

98,077

DESIGN FOR A BOTTLE

George H. Laird, West Medford, Mass., assignor to C. H. Graves & Sons Company, Boston, Mass.,
a corporation of Massachusetts

Application November 13, 1935, Serial No. 59,522

Term of patent 14 years

To all whom it may concern:

Be it known that I, George H. Laird, a citizen of the United States and residing at West Medford, in the county of Middlesex, and State of Massachusetts, have invented a new, original, and ornamental Design for a Bottle, of which the following is a specification, reference being had to the accompanying drawing, forming a part thereof.

In the drawing:

Fig. 1 is a side elevational view of a bottle showing my new design.

Fig. 2 is a sectional plan view thereof taken substantially along the line II—II of Fig. 1.

Fig. 3 is a fragmentary vertical sectional view taken along the line III—III of Fig. 1 and showing the arrangement of the concave area.

I claim:

The ornamental design for a bottle substantially as shown and described.

Signed at West Medford, in the county of Middlesex and State of Massachusetts, this 8th day of November, 1935.

GEORGE H. LAIRD.
